UNITED STATES PATENT OFFICE.

HONARE MORIN, OF AUBURN, MAINE.

SOLE-LEVELING MACHINE.

1,269,486.

Specification of Letters Patent. Patented June 11, 1918.

Application filed August 31, 1917. Serial No. 189,144.

To all whom it may concern:

Be it known that I, HONARE MORIN, a citizen of Canada, residing at Auburn, in the county of Androscoggin and State of Maine, 5 have invented certain new and useful Improvements in Sole-Leveling Machines; and that I do hereby declare the following to be a full, clear, and exact description of the invention, such as will enable others skilled 10 in the art to which it appertains to make and use the same.

This invention relates to improvements in sole leveling machines, and has for one of its objects to provide an improved mounting 15 for the leveling roller permitting floating movement of the latter under tension as it traverses the surface of the shoe sole.

Another object of the invention is the provision of a novel and conveniently controlled driving mechanism for the reciprocating leveling roller carriage.

A still further object is the provision of an improved shoe and last support embodying novel features of construction permitting 25 the lasts and toe supports to be adjusted longitudinally of the machine and vertically to accommodate shoes of various sizes.

With these and other objects in view, the 30 invention consists in the novel construction, combination and arrangement of parts as will be hereinafter specifically described, claimed and illustrated in the accompanying drawings, in which:

35 Figure 1 represents a side elevation of the improved machine,

Fig. 2 represents a front elevation thereof,

Fig. 3 represents an enlarged detail view 40 in side elevation of the front end of the leveling roller carriage and the shoe-supporting devices,

Fig. 4 represents a horizontal sectional view on the line 4—4 of Fig. 1,

Fig. 5 represents a detail sectional view 45 through the support for the leveling roller,

Fig. 6 represents a vertical detail sectional view on the line 6—6 of Fig. 1,

Fig. 7 represents a fragmentary sectional view 50 on the line 7—7 of Fig. 5, and

Fig. 8 represents a vertical sectional view through the toe-supporting pad for the shoe.

Referring to the drawings in detail, wherein similar reference numerals designate corresponding parts throughout the 55 several views, the numeral 10 indicates generally a supporting frame structure for the

machine, which includes a horizontally disposed table or bed plate 11, provided with a longitudinally extending slot 12 receiving the base member 13 carrying the toe-supporting pad 14 for the toe of the shoe. The base member 13 is slidable longitudinally in the slot or groove 12, and is secured in adjusted position, to accommodate shoes of varying lengths, by a lock screw 15. The toe pad 14 is mounted for vertical adjustment upon a screw 16, threaded in a vertical recess 17 formed in the base member 13 and secured in adjusted position by a hand wheel 18, having an internally threaded aperture fitting the screwthreads of the screw 16, whereby the latter is rigidly secured in adjusted position with relation to the base member.

In front of the toe pad 14 a vertically movable slide rod or bar 19 is fitted in a guide 20 carried by the table 11, and carries at its upper terminal a last-supporting pin 21, which is adjustable vertically with the bar 19. The lower terminal of the bar 19, which extends between and forwardly of the front supporting legs of the frame structure 10 is provided with gear teeth 22, which mesh with a pinion 23 rotatably supported on a shaft 24 journaled in the front supporting legs of the frame structure. A hand lever 25 is rigidly connected with the shaft 24 and extends upwardly alongside of the supporting leg of the frame, terminating at a point conveniently near the table 11. By 50 oscillating the hand lever 25 the gear wheel 23 is actuated to elevate or lower the last-supporting rod 20, and the lever is locked in adjusted position by a preferred type of locking device, designated generally by the 55 numeral 26.

A pair of opposed levers 27 is pivotally mounted at 28 to the front end of the table 11 and carry a pair of heel-clamping plates 29, which terminate adjacent the last-supporting pin 21 and are designed to firmly clamp the heel portion of the shoe 30. The lower terminals of the levers 27 are pivotally connected with the upper terminals of a second pair of levers 31, which are pivotally supported at 32 upon the frame structure 10, and are connected at their lower terminals by a pair of curved links 33 with a connecting rod 34. A foot actuated pedal 35 is pivotally supported by a depending bracket 110 arm 36 carried by the frame structure 10 and is pivotally connected at 37 with the

lower terminal of the connecting rod 34, at a point forwardly of the pivotal connection between the pedal and the supporting arm 36 therefor, whereby when the pedal is depressed, the levers 27 are swung so as to cause the clamps 29 to firmly engage the opposed side portions of the heel of the shoe 30.

A substantially U-shaped screw supporting member 38 is pivotally secured at its opposite ends to the front terminal of the table 11, as indicated at 39, and the web portion thereof is provided with an internally threaded aperture receiving a screw 40, carrying an adjusting hand wheel 41 at its upper terminal and a heel-engaging block 42 at its lower terminal, adapted, as the screw 40 is advanced, to engage and level the heel portion of the shoe.

20 The upper part of the frame structure 10 is provided with a horizontally disposed and longitudinally slotted guide or support 43 for the reciprocable carriage 44, having gear teeth 45 formed in the lower surface thereof. The front terminal of the carriage 44 is hingedly connected at 46 with a frame 47, which is movable with the carriage 44 during its reciprocating movement and is movable independently thereof on the pivot 46. The top of the front end of the pivoted frame 47 is provided with a screw threaded aperture 48, receiving the hollow screw 49, carrying a hand wheel 50 at its upper terminal. The lower terminal of the screw 49 constitutes an abutment for an expansion spring 51, which normally retains the leveling roller supporting yoke 52 in downwardly extended position. As is clearly evident by reference to Fig. 5 the yoke 52 is substantially U-shaped and the web portion thereof is formed with an arcuate slot 53, receiving the headed terminal of a rod 54, permitting the yoke 52 to oscillate freely in the front end of the pivoted frame 47.

45 The apertured end 55 of a presser rod 56 is confined between the web portion of the U-shaped yoke 52 and a washer 57 engaged underneath the spring 51, and the rear terminal of the presser rod 56 is connected 50 by a joint 58 with a spring pressed plunger 59, extending within a recess 60 formed in the carriage 44 and engaging an expansion spring 61 located therein. The tension of the spring 61 normally tends to tilt the pivoted frame 47 forwardly upon its pivotal axis 46. A shaft 62 is journaled in the parallel terminals of the U-shaped yoke 52 and supports the concaved leveling roller 63, which is confined between said parallel 55 terminals. The vertical movement of the opposed terminals of the roller 63 incident to the oscillation of the roller over the irregular surface of the shoe sole is guided by vertically disposed slots 64 formed in the 60 vertically movable guide blocks 65 slidably

mounted in vertical grooves 66 formed in the side members of the pivoted frame 47. The tension of the spring 51 normally acts to maintain the roller 63 in rolling contact with the surface of the shoe sole, and by 70 properly adjusting the screw 49 the tension may be varied as desired.

To manually increase the pressure exerted by the roller 63 against the shoe sole or to manually adjust said roller to maintain 75 it in rolling contact with the shoe sole, an angular handle 67 is connected with the yoke 52, and is extended laterally and forwardly of the frame 47 into convenient reach of the operator of the machine.

The lower terminal of the portion of the pivoted frame 47 supporting the leveling roller 63 is provided with inwardly directed fingers 70, which slide upon relatively stationary guides 71 carried by the frame structure 10. The guides 71 project forwardly on opposite sides of the toe pad 14 and are curved downwardly at their front terminals, as indicated at 72, to permit the frame structure 47 to swing downwardly under the influence of the spring 61 as the roller 63 rolls over the comparatively low heel portion of the shoe 30. The fingers 70 are confined beneath guide flanges 74 carried by and adjustable with a vertical extension 75 carried by the adjustable toe pad supporting base member 13. As clearly shown in Fig. 3, the guide flanges 74 terminate at a point rearwardly of the toe of the shoe 30, so as to release the spring actuated frame 47 prior to 100 the engagement of the leveling roller 63 with the shoe sole.

As stated, the reciprocable carriage 44 is provided with downwardly projecting gear teeth 45, and these teeth mesh with a gear 105 segment 76 supported upon a shaft 77, which latter is journaled in bearings 78 provided in the frame structure 10. A gear wheel 79 is also non-rotatably secured to the shaft 77 and meshes with a relatively small 110 pinion 80 carried by a shaft 81, which latter is mounted in relatively stationary bearings 82 carried by the frame structure 10.

The rear portion of the frame structure 10 underneath the carriage 44 is provided with a horizontally disposed guide 83 supporting a longitudinally movable frame structure consisting of a pair of spaced sections 84, which are connected by the inverted U-shaped reinforcing bar 85 and are arranged in spaced relation to each other to accommodate the bearing 82 of the shaft 80. The terminals of the frame sections 84 abut shock absorbing springs 86 housed in recesses 87 provided at the terminals of the 125 guide or support 83.

Shafts 88 and 89 are mounted in bearings 90 and 91 carried by and movable with the frame sections 84 and the shaft 88 carries a friction wheel 92, which, when the frame 130

84 is moved rearwardly, engages and drives the friction wheel 93 carried by the shaft 81. The shaft 89 supports a friction wheel 94, which, when the frame 84, is moved forwardly, engages and drives the friction wheel 93 and shaft 81 in the direction opposite to that in which it is driven when engaged by the friction wheel 92.

The frame sections 84 are rigidly connected with the upper terminals of a depending V-shaped member 96, which supports an idler shaft 97 carrying the relatively non-rotatable pulleys 98 and 99. The pulley 98 is connected by a belt 100 with the pulley 101 carried by the shaft 88, and the other pulley 99 carried by the intermediate shaft 97 is connected by a belt 102 with a pulley 103 carried by the shaft 89. The belt 102 is crossed, as clearly shown in Fig. 1, whereby the shafts 88 and 89 are driven in opposite directions. A drive shaft 104 is mounted in bearings 105 carried by the frame section 84, and is connected by a belt 106 with the pulley 103. The pulley 107, carried by the shaft 104, is designed for connection with a suitable drive shaft (not shown), whereby the machine is operated.

From the foregoing, it is evident that in operation the shoe last is supported upon the supporting pin 21, and the latter is elevated to the desired position by proper adjustment of the hand lever 25. The toe pad 14 is subsequently adjusted vertically and longitudinally to assume the correct position to support the toe of the shoe, and by depressing the pedal 35 the clamping members 29 are caused to firmly grip the heel portion of the shoe. Assuming that the drive pulley 107 is rotated in the direction of the arrow in Fig. 1, the movable frame 84 is moved rearwardly so as to engage the friction wheel 92 with the friction wheel 93, so as to cause the carriage 44 to move forwardly. For convenience in adjusting the frame 84, an arm 45 109 is rigidly connected therewith and is pivotally attached at its forward extremity with an arm 110 carried by a shaft 111 on which is mounted a hand lever 112. The rotary movement of the drive pulley 107 is transmitted to the carriage 44 through the belts 106, 102, 100, friction wheels 92 and 93, gear wheels 80 and 79 and finally through the gear segment 76 to the toothed portion 45 of the carriage. During the forward movement of the carriage, the leveling roller 63 rolls over the surface of the shoe sole 30, thereby effectively leveling the latter. The roller 63 and its shaft 62 are retained in rolling contact with the shoe sole by the tension of the spring 51, and the shaft 62 is permitted to oscillate in order to maintain the roller in snug engagement with the surface of the sole by the sliding contact of the shaft with the grooves 64 and the slidably mounting of the supporting blocks 65. In

order to reverse the direction of movement of the reciprocable carriage 44, the lever 112 is pulled forwardly, so as to cause the friction wheel 94 to engage the friction wheel 93, and simultaneously disengaging the friction wheel 92 from the wheel 93.

What I claim is:

1. In a sole leveling machine, a movable carriage, a frame pivotally secured thereto, guide blocks slidably mounted in said frame, 75 and a spring actuated leveling roller journaled in said blocks.

2. In a sole leveling machine, a reciprocable carriage, a frame pivotally secured thereto, a spring pressed rod supported in 80 said frame, a yoke carried by and movable relatively to the rod, and a leveling roller supported by said yoke.

3. In a sole leveling machine, a carriage, a frame pivotally secured thereto, spring 85 presser means for said frame, a rod movable vertically in said frame, a yoke carried by and movable relatively to said rod, a leveling roller journaled in said yoke, and vertically movable guide blocks for said 90 roller slidably supported in said frame.

4. In a sole leveling machine, a carriage, a frame pivotally secured to the carriage, guide blocks slidably mounted in said frame, and provided with vertical recesses in their 95 inner surfaces, a leveling roller, a supporting shaft for said leveling roller, said shaft having its ends seated in said recesses.

5. In a sole leveling machine, a reciprocable carriage, a frame pivotally secured 100 thereto, guide blocks slidably mounted in said frame a spring pressed rod supported in said frame, a yoke carried by and movable relatively to said rod, a shaft journaled in said yoke and having its end seated 105 in said guide block, and a leveling roller supported by said shaft.

6. In a sole leveling machine, a reciprocable carriage, a frame pivotally secured thereto, a spring pressed rod supported in 110 said frame, a yoke carried by and movable relatively to the rod, a shaft journaled in the arms of said yoke, a leveling roller carried by said shaft, and guide blocks slidably carried by said frame and provided 115 with vertical recesses in their inner faces, the ends of said shaft extending into said recesses in said guide blocks.

7. In a sole leveling machine, a frame pivotally secured thereto, a spring pressed rod supported in said frame, a yoke carried by and movable relatively to the rod, a leveling roller supported by said yoke, and a spring controlled presser rod connected to said spring pressed rod and normally 120 tending to tilt the frame forwardly.

8. In a sole leveling machine, a carriage, a frame pivotally secured thereto, spring presser means for said frame, a rod movable vertically in said frame, a yoke carried 130

- by and movable relatively to said rod, a leveling roller journaled in said yoke, vertically movable guide blocks for said roller slidably supported by said frame, and a 5 spring controlled presser rod connected to said vertically movable rod and normally tending to tilt said frame forwardly.
9. In a sole leveling machine, a reciprocable carriage, a frame pivotally secured thereto, 10 a spring pressed rod supported in said frame, a yoke carried by and movable relatively to the rod, a shaft journaled in the arms of said yoke, a leveling roller carried by said shaft, guide blocks slidably carried by said 15 frame and provided with vertical recesses in their inner faces, the ends of said shaft extending into said recesses, and a spring controlled presser rod connected to said spring pressed rod and normally tending to 20 tilt said pivoted frame forwardly.
10. A sole leveling machine, a carriage, a frame pivotally secured thereto, guide blocks slidably mounted in said frame and provided with vertical recesses in their inner surfaces, a leveling roller, a supporting shaft for said leveling roller, said shaft having its ends seated in said recesses, and a spring controlled presser rod connected to 25 said frame and normally tending to tilt the 30 frame forwardly.
11. In a sole leveling machine, a reciprocable carriage, a frame pivotally secured thereto, a spring pressed rod supported by said frame, a yoke carried by and relatively 35 movable to the rod, a leveling roller supported by said yoke, and a hand lever connected to said yoke for manually forcing said roller into a sole engaging position.
12. In a sole leveling machine, a carriage, 40 a frame pivotally secured thereto, guide blocks slidably mounted in said frame, and provided with vertical recesses in their inner surfaces, a leveling roller, a supporting shaft for said leveling roller, said shaft having its ends seated in said recesses, and a 45 hand lever connected to said pivoted frame for manually forcing said roller into a sole engaging position.
13. In a sole leveling machine, a reciprocable carriage, a frame pivotally secured 50 thereto, a yoke carried by and movable relatively to the frame, a leveling roller supported by said yoke, and a hand lever connected to said yoke for manually forcing said roller into a sole engaging position.
14. In a sole leveling machine, a frame structure, a movable carriage mounted thereon, a spring actuated frame pivotally supported by said carriage, a leveling roller 55 mounted in said frame, and a hand lever connected to said pivoted frame manually forcing said roller into a sole-engaging position.
15. In a sole leveling machine, a movable 60 carriage, a frame pivotally supported by
- said carriage, a leveling roller mounted in said frame for limited vertical and oscillatory movement independent of the frame, means for holding said roller in a sole engaging position, and a hand lever for manually forcing the roller into engagement with a shoe sole.
16. In a sole leveling machine, a frame, a vertically movable last supporting rod mounted upon the frame, rack teeth formed upon said rod, a shaft carried by said frame, a gear carried by said shaft and meshing with said rack teeth to vertically move the rod upon rotation of the shaft, means for locking said shaft against rotation to hold 75 said rod in adjusted position, shoe clamping means carried by said supporting frame structure, a foot lever, and a series of levers connecting said foot lever, and shoe clamping means to move the clamping means into 80 or out of clamping position upon operation of the foot lever.
17. In a sole leveling machine, a frame structure, a reciprocable carriage carried by 85 said frame structure, a frame pivotally supported by said carriage, a leveling roller mounted in said frame for limited vertical and oscillatory movement independently of the frame, means for holding said roller in sole engaging position, a hand lever for 90 manually forcing the roller into engagement with a shoe sole, shoe clamping means supported by said frame structure, a foot lever, and a series of levers connecting said foot lever and shoe clamping means to move the 95 clamping means into or out of clamping positions upon operation of said foot lever.
18. In a sole leveling machine, a frame structure, a reciprocable carriage supported thereby, a frame pivotally secured to the 100 frame, a spring pressed rod supported in said frame, a yoke carried by and movable relatively to the rod, leveling roller, supported by said yoke, shoe clamping means carried by said frame structure, a foot lever, 105 and a series of levers connecting said foot lever and said shoe clamping means to move the clamping means into and out of the 110 clamping positions upon operation of the foot lever.
19. In a sole leveling machine, a frame structure, a reciprocable carriage carried thereby, a frame pivotally secured to the carriage, spring presser means for said frame, a rod movable vertically in the frame, 115 a yoke carried by and movable relatively to said rod, a leveling roller journaled in said yoke, vertically movable guide blocks for said roller slidably supported in said pivoted frame, shoe clamping means supported by 120 the frame structure, a foot lever, and a series of levers connecting said foot lever and shoe clamping means to move the clamping means into and out of clamping position upon 125 operation of the foot lever.
- 130

20. In a sole leveling machine, a frame structure, a reciprocable carriage carried by the frame structure, a frame pivotally secured to the carriage, a spring pressed rod supported in said frame, a yoke carried by and movable relatively to the rod, a shaft journaled in the arms of said yoke, a sole leveling roller carried by said shaft, guide blocks slidably carried by said frame and 5 provided with vertical recesses in their inner spaces, the ends of said shaft extending into said guide blocks, a hand lever connected to said yoke for manually forcing said roller 10
- into a sole engaging position, shoe clamping means supported by the frame structure, a 15 foot lever, and a series of levers connecting said foot lever and shoe clamping means to move the clamping means into and out of clamping positions upon operation of the foot lever. 20

In testimony whereof I affix my signature in presence of two witnesses.

HONARE MORIN.
